PREPARATION OF CYCLOPENTADIENYL MANGANESE COMPOUNDS

Jerome E. Brown, Detroit, Earl G. De Witt, Royal Oak, Mich., and Hymin Shapiro, Baton Rouge, La., assignors to Ethyl Corporation, New York, N. Y., a corporation of Delaware

No Drawing. Application July 24, 1957
Serial No. 673,768

1 Claim. (Cl. 202—46)

This invention relates to the manufacture of organo metal carbonyl compounds and more particularly to the separation and recovery of cyclopentadienyl manganese tricarbonyl compounds, and especially alkylcyclopentadienyl manganese tricarbonyls.

Cyclopentadienyl manganese tricarbonyl compounds have been found to be exceptionally effective antiknocks for use in fuels, for spark plug ignition internal combustion engines. These compounds not only have exceptional effectiveness as antiknocks but also many of these compounds, principally the liquid compounds, have auxiliary properties which make them entirely practical and desirable for commercial use. These auxiliary properties include high solubility in fuels, such as gasoline, and thermo-stability either alone or in gasolines which makes these compounds entirely satisfactory for use under the widely varying conditions to which gasoline and other fuels are normally subjected. Possibly of even greater importance, these compounds do not tend to form any appreciable deposits on the engine pistons, valves and spark plug surfaces and likewise are not abrasive to the engine parts as are characteristic of iron compounds.

A preferred method of manufacture of these cyclopentadienyl manganese tricarbonyl compounds comprises reacting carbon monoxide with a bis(cyclopentadienyl) manganese compound, e. g. bis(methylcyclopentadienyl) manganese. In this reaction, only one of the two cyclopentadienyl radicals in the bis-compound is used in forming the product. The other cyclopentadienyl radical is lost as byproduct, normally polymerizing to a soft, sticky material. This byproduct causes difficulty in subsequent recovery of the cyclopentadienyl manganese tricarbonyl as hereinafter described.

The bis(cyclopentadienyl) manganese compound is normally made by reaction of a cyclopentadienyl sodium compound or other alkali metal compounds with a manganese chloride or other salt. Sodium chloride is formed as a byproduct, two moles per mole of the bis-manganese product. The carbon monoxide is normally added directly to this reaction product, forming a second reaction product of the desired cyclopentadienyl manganese tricarbonyl. This second reaction product also contains many impurities, including the polymer, noted above, sodium salts, unreacted manganese salts and the like which makes product separation and materials handling extremely difficult. These impurities in most cases are present even in greater quantities than the desired product.

It is accordingly an object of this invention to provide an improved method for manufacture of cyclopentadienyl manganese tricarbonyl compounds. Another object is to provide a method for the recovery and separation of these compounds from a reaction product containing inorganic and polymeric impurities. A more specific object is to provide a simple and convenient method of separating cyclopentadienyl manganese carbonyl compounds from the reaction product, which method provides a high ultimate yield of product and which provides easy

2

and cheap disposal of the byproduct residue. Another object is to provide a method of the above type suitable for large scale commercial production of cyclopentadienyl manganese tricarbonyls, particularly alkylcyclopentadienyl manganese tricarbonyl compounds. Other objects and advantages of this invention will be apparent for the following description and appended claims.

These and other objects of this invention are accomplished if the cyclopentadienyl manganese tricarbonyl compound is steam distilled from the reaction product while maintaining the byproduct in a fluid state in a liquid hydrocarbon, particularly aromatic hydrocarbons, having at least 12 carbon atoms. More specifically, the crude reaction mixture, which normally contains about equal quantities of the desired cyclopentadienyl manganese tricarbonyl product and impurities, such as organic polymer and salts, is suspended in the high boiling liquid, preferably in contact with a suitable volume of water which is immiscible with the high boiling liquids defined above. Steam is then injected into the liquid suspension or solution to distill the desired product as a water azeotrope. During the steam distillation, the system is preferably agitated so as to maintain essentially a homogeneous mixing of the immiscible phases. Normally, it is preferred to remove any solvent from the crude reaction product by a straight distillation, vacuum or pressure, either prior to or after addition of the high boiling liquid.

The present recovery process is particularly desirable due to the essentially complete recovery of the desired product. The large quantities of polymeric and inorganic purities are maintained in a highly fluid state, the organic phase normally being dissolved or suspended in the high boiling liquid and the inorganic phase being dissolved in the aqueous phase. Under these conditions the impurities can be readily removed from the steam still, such that the steam still is left clean and the byproduct is in an easily handled form. Also, the polymeric material and inorganic content of the impurities are easily separated for efficient disposal or for treatment to recover their valuable components, such as the manganese values and the cyclopentadienyl polymeric material. The manganese values can be converted to additional manganese salt which then can be reprocessed. The cyclopentadienyl polymeric material can be either cracked to monomer and recycled or burned for fuel value.

Another distinct advantage in the use of the high boiling liquid is the unexpected reduction in foaming and frothing which normally accompanies steam distillation of the crude reaction mixture in the absence of such high boiling liquids. This problem is very serious in large scale commercial operation since it materially reduces the throughput capacity of the process equipment. Also, the use of high boiling liquids in accordance with this invention materially increases the steam efficiency during the recovery operation.

The following are typical examples of the present invention which are presented for the purpose of illustrating the beneficial characteristics of the present process. All units in the following examples are given in parts by weight.

EXAMPLE I

A crude reaction product (1310 parts) prepared as defined below was diluted with 393 parts of a liquid consisting essentially of methylated naphthalenes which is commercially marketed as a light phenol extract and obtained as the bottoms of a distillation of the product recovered obtained from steam cracking of oil gas. This material has an initial boiling point of about 270° C. This mixture was then vacuum distilled at a temperature of 135° C. in distillation equipment having a ten plate column maintained at 50 mm. mercury pressure. A 5:1

reflux ratio was employed and the mixture in the pot was continuously stirred. 540 parts of diethylene glycol dimethyl ether were removed as distillate. 750 parts of water were then added to the solvent-free reaction mixture in a steam still and steam was injected (40 lbs./sq. in. atm. pressure). An azeotrope distilled at a temperature of 100 to 104° C. which was collected and permitted to separate into separate phases. 331 parts of the organic distillate (methylcyclopentadienyl manganese tricarbonyl) were recovered. Essentially no foaming or frothing occurred during the steam distillation. The steam residue consisted of both an aqueous phase and the methylated naphthalene phase and both were highly fluid and could be readily discharged from the steam still.

The manganese compound recovered as above is then subjected to fractionation and this purified product is thereafter blended with gasoline. The following Table I presents data showing the octane increase of a commercial gasoline having an initial boiling point of 94° F. and a final boiling point of 390° F. The antiknock value of the fuel as determined by the ratings are given in octane numbers for figures below 100 and in Army-Navy performance numbers for values above 100. The method of determining performance numbers is explained in the booklet "Aviation Fuels and their Effect on Engine Performance," NAVAER-06-5-501, USAF T. O. No. 06-5-54, published in 1951.

Table I

C ₆ H ₇ Mn (CO) ₃ , g. metal/gal.	Octane Rating
0	83.1
1.0	92.7
2.0	95.8
3.0	98.0
5.0	102.0

The crude reaction mass treated above was prepared reacting 1448 parts of sodium metal with 1835 parts of methylcyclopentadiene in 708 parts of diethylene glycol dimethyl ether. This reaction was conducted at a temperature of 111° C. The system was agitated to disperse the sodium prior to reaction with the methylcyclopentadiene. To this reaction mixture was added 708 parts of manganese chloride and the temperature was raised to about 126° C. while agitating the reaction mixture. After completion of this reaction, carbon monoxide was added (305 lbs./sq. in.) and the temperature was raised to 193° C. Vigorous agitation was employed throughout this reaction. This crude reaction mixture, protected against exposure to air or moisture, was then treated to recover the methylcyclopentadienyl manganese tricarbonyl in accordance with the above procedure.

EXAMPLE II

Example I was repeated except that 383 parts of a commercial product, Enjay aromatic HB 9700, manufactured by Esso Standard Oil Company, was used in place of the methylated naphthalene of Example I. This commercial product is predominately aromatic hydrocarbons containing both benzene and naphthalene derivatives and has an initial boiling point of about 145° C. at 20 mm. mercury pressure. The methylcyclopentadienyl manganese tricarbonyl product was recovered in essential quantitative yields and the distillate residue was highly fluid and could be readily discharged from the steam still. Due to the somewhat lower boiling point of the Enjay material, a small amount of the high boiling liquid was recovered with the product but this material could thereafter be separated from the product by fractionation.

EXAMPLE III

Example I was repeated except that the diethylene glycol dimethyl ether solvent was vacuum distilled prior

to the addition of the water and the methylated naphthalene liquid. Beginning with 1113 parts of reaction product, 437 parts of the solvent were recovered. Also, steam distillation was begun prior to the addition of the methylated naphthalenes. About 250 parts of the methylcyclopentadienyl manganese tricarbonyl were recovered and then 334 parts of the methylated naphthalene was added to the partially distilled reaction product. The remaining methylcyclopentadienyl manganese tricarbonyl product (60 parts) where thereafter steam distilled and recovered. Recovery of the product from the crude mixture was essentially complete and the distillate residue was highly fluid and could be readily removed from the process equipment.

EXAMPLE IV

Example III was repeated except that 1164 parts of crude reaction mass was treated to recover 480 parts of the solvent and 90 parts of the methylcyclopentadienyl manganese tricarbonyl were recovered prior to the addition of the methylated naphthalene liquid. A total of 310 parts of the methylcyclopentadienyl manganese tricarbonyl were recovered. The distillate residue was highly fluid and could be readily discharged from the vessel.

EXAMPLE V

Example I was repeated employing a different reaction mass which contained more diethylene glycol dimethyl ether. Beginning with a reaction of 1096 parts, 604 parts of solvent were removed during vacuum distillation and 265 parts of the product were steam distilled of a total of 318 parts prior to the addition of the methylated naphthalenes.

EXAMPLE VI

Example I is repeated except that cyclopentadiene is reacted with a molar equivalent of potassium metal in a dispersion in mineral oil, 1:1 weight ratio of metal and oil. The reaction is conducted at 50° C. Manganese acetate in a 1:2 mole ratio is then added to this reaction product and reacted at a temperature of 130° C. This second reaction mixture is thereafter carbonylated at 175° C., using 600 p. s. i. g. carbon monoxide pressure. The reaction mixture, protected against air and moisture, is then distilled in accordance with the procedure of Example I, using ethylated naphthalene as the high boiling liquid. The cyclopentadienyl manganese tricarbonyl product is recovered in essentially complete yield and the steam distillation residue is highly fluid and can be readily discharged from the steam still.

EXAMPLE VII

Example I is repeated except that indene is employed in place of the methylcyclopentadiene and diethylene glycol dibutyl ether is used as the solvent. About 3 times the weight of solvent is used in this run. Manganese bromide is reacted instead of manganese chloride with the first reaction product. The indenyl manganese tricarbonyl product is recovered in accordance with the procedure in Example I except that triethyl benzene is used as the high boiling liquid.

EXAMPLE VIII

Example I is repeated except that diethylcyclopentadiene is reacted with the sodium in cyclohexylamine. Manganese iodide is used to react with the diethylcyclopentadienyl sodium. Anthracene is employed as the high boiling solvent during the steam distillation. Similar results are obtained.

EXAMPLE IX

Example I is repeated except that lithium is used as the alkali metal and a 50-50 weight by weight mixture of biphenyl and biphenyl ether is employed in the steam distillation. The formation of the methylcyclopentadienyl lithium compound is carried out at 200° C. and the meth-

yl cyclopentadiene dimer is fed directly to the reaction mixture. Essentially quantitative product recovery is obtained and the product residue remains in a fluid state.

EXAMPLE X

Example I is repeated except that a low ethylene polymer having an initial boiling point of about 300° C. is used in place of the methylated naphthalene. 425 parts of the triglycol dichloride are added after the steam distillation has progressed to recover approximately 50 percent of the product.

EXAMPLE XI

Example I is repeated except that phenyl naphthalene is used. In this example only about 250 parts of water are added prior to the steam distillation.

EXAMPLE XII

Example I is repeated except that a low polystyrene polymer having an initial boiling point of about 275° C. is employed in place of the methylated naphthalene. The product is essentially completely recovered and the steam still residue is highly fluid and can be easily drained from the steam still.

EXAMPLE XIII

Example I is repeated except that reaction mixture contains indenyl manganese tricarbonyl instead of the methylcyclopentadienyl compound and a low butadiene polymer is used as the high boiling liquid. Similar results are obtained.

When the above examples are repeated using different reflux ratios, e. g., 1:1, 4:1 and 10:1, similar results are obtained. Either superatmospheric or subatmospheric pressures can be used in the above examples with generally equal results, e. g. 0.5 atmosphere, 10 atmospheres and 30 atmospheres. In the straight distillation of solvent somewhat better separations are obtained with pressure operations.

The following Table II presents in tabular form Examples XIV to XVIII inclusive. These examples illustrate the process of this invention using different types of reaction products, solvents, and high boiling liquids for suspending the reaction product residue. The reaction products treated in Examples XIV and XV are prepared similar to the procedure illustrated in Example I except that cyclopentadiene and indene are employed instead of methylcyclopentadiene. In all of these examples, essentially complete recovery of the desired manganese compound is obtained and the residue is highly fluid and can be readily discharged from the distillation equipment.

availability as byproducts, particularly from the petroleum refining industry. The most desirable aromatic hydrocarbons are the naphthalene type, particularly the alkylated naphthalenes, either as pure compounds or as mixtures with benzene derivatives or anthracene derivatives.

Typical examples of suitable aromatic hydrocarbons are diisopropyl benzene, triisopropyl benzene, tributyl benzene, diphenyl, terphenyl, naphthalene, methylated naphthalenes, either mono- or polysubstituted, anthracene, including the alkyl derivatives of anthracene such as the mono-, di- or higher methyl substituted anthracenes, ethyl anthracenes, dibutyl anthracenes, and the like. In some cases, aromatic hydrocarbons which contain other substitutions, such as halogen substitutions, act similarly to hydrocarbons and can be considered equivalents. Examples of these are the chlorinated benzenes and naphthalenes. Other hydrocarbons suitable for use in this invention are dodecane, pentadecane, octadecane, octacosane and the like.

The particular high boiling liquid to be preferred in this invention depends somewhat on the product to be recovered. In general, the liquid should have a boiling point from 0-150° C. degrees above the boiling point of the product and preferably from 50-100° C. degrees.

With liquids having lower boiling points, an excessive quantity of liquid is removed with the product and must be separated by fractionation or similar techniques. Higher boiling point liquids do not adequately flush or purge the product from the distillation equipment.

The concentration of the high boiling, water-immiscible liquid can range from about 0.01 to about 10 parts/part of the cyclopentadienyl manganese tricarbonyl compound in the crude reaction mixture. A more preferred concentration is from 1 to 5 percent. In general, it is preferred to use as low a concentration as is possible while still maintaining a fluid system under processing conditions. This is particularly true when it is desired to dispose of the fluid residue by burning, using the high boiling liquid as a source of fuel. Higher concentrations can be used although there is no particular advantage from a processing standpoint and actually greater quantities are disadvantageous, due to reduction of product throughput in the recovery equipment and increased costs of using and handling greater volumes of material.

The quantity of water to be added to the reaction mass prior to the steam distillation is not critical and, in fact, its addition can be eliminated, if desired. Normally, however, a weight of water ranging from about 1/3 to 5 times the weight of the reaction mass is used. Usually, the reaction mixture is suspended in from about one-half to about equal quantities of water before beginning the steam distillation.

Table II

Example	Reaction Product	Solvent	High Boiling Liquid	Parts R. P./ H. B. L. ¹	Steam, p. s. i. g.	Inorganic Salt

¹ Weight of product in the crude reaction product/weight of high boiling liquid.

A wide variety of high boiling water immiscible hydrocarbon liquids can be employed in the process of this invention selected from the group consisting of hydrocarbons, particularly aromatic hydrocarbons, having at least 12 carbon atoms and usually not greater than 30 carbon atoms and certain ethers and esters, such as are listed above. The aromatic hydrocarbons are by far the most preferred due to the unexpected fluidity of the distillate residue in these liquids and due to their low cost and

The present process is suitable for recovery of a wide variety of cyclopentadienyl manganese tricarbonyl compounds and is particularly desirable for recovery of such compounds having cyclopentadienyl radicals containing from 5 to 13 carbon atoms. These latter compounds have molecular weights up to about 315. Typical examples of cyclopentadienyl manganese tricarbonyl compounds which can be recovered in accordance with this invention are cyclopentadienyl manganese tricarbonyl,

methylcyclopentadienyl manganese tricarbonyl, indenyl manganese tricarbonyl, ethyl cyclopentadienyl manganese tricarbonyl, phenyl methylcyclopentadienyl manganese tricarbonyl and the like.

The above cyclopentadienyl manganese tricarbonyl compounds can be prepared from corresponding bis(cyclopentadienyl) alkali metal compounds by reaction with carbon monoxide. For example, cyclopentadienyl manganese tricarbonyl is prepared by the reaction of carbon monoxide with bis(cyclopentadienyl) manganese. Likewise, the methyl derivative, i. e. methylcyclopentadienyl manganese tricarbonyl, is prepared by reacting carbon monoxide with bis(methylcyclopentadienyl) manganese. Thus, corresponding cyclopentadienyl manganese tricarbonyl compounds can be prepared from bis(ethylcyclopentadienyl) manganese, bis(n-octyl cyclopentadienyl) manganese, bis(indenyl) manganese, bis(fluorenyl) manganese and the like.

The above compounds can be prepared by a number of known processes and, in general, are synthesized in three separate steps. An alkali metal (e. g. sodium, potassium or lithium) cyclopentadienyl compound is prepared by reaction of the corresponding alkali metal with the cyclopentadiene hydrocarbon in a suitable solvent, such as a hydrocarbon or ether, e. g. toluene, diethylene glycol dimethyl ether or tetrahydrofuran. This reaction is conducted with agitation at a temperature of from 0 to 250° C., preferably above 100° C., using either the cyclopentadiene monomer or dimer. This reaction mixture is then reacted with a manganese salt. Suitable manganese salts are halides, such as the chloride or a

bromide, manganous sulfate or organic salts, such as the acetate. In general, this reaction is conducted in ether type solvents, such as those discussed above, at a temperature of 100° to 250° C., usually from 130 to 175° C. This second reaction product is then reacted with carbon monoxide usually at pressures of from 100 to 500 lbs./sq. in., although both lower and higher pressures can be used. This carbonylation reaction is normally conducted at temperatures of from 150 to 250° C. using agitation.

The crude reaction mixture as prepared above should be protected from contact of air or moisture since materially greater difficulty is encountered in the steam distillation after prolonged exposure of the crude mixture to either air or moisture. Normally, the crude mixture is maintained under an inert atmosphere prior to distillation or the crude mixture is fed directly to the distillation equipment in a closed system.

We claim:

20 In a process for producing cyclopentadienyl manganese tricarbonyl compounds in which a cyclopentadiene compound is reacted with an alkali metal, the reaction product is thereafter reacted with a manganous salt and the product of the latter reaction is then reacted with carbon monoxide in the presence of a solvent, the improvement comprising steam distilling said cyclopentadienyl manganese tricarbonyl compound in the presence of from about 0.01 to about 10 parts per part of said cyclopentadienyl manganese tricarbonyl compound of a hydrocarbon liquid having at least 12 carbon atoms.
